UNITED STATES PATENT OFFICE.

CARL R. ENGLUND, OF WEST LONG BRANCH, AND ARTHUR HADDOCK, OF EAST ORANGE, NEW JERSEY, ASSIGNEES TO WESTERN ELECTRIC COMPANY, INCORPORATED, OF NEW YORK, N. Y., A CORPORATION OF NEW YORK.

DESIGN FOR A LOOP ANTENNA.

Application filed May 26, 1923. Serial No. 6,288. Term of patent 14 years.

To all whom it may concern:

Be it known that we, CARL R. ENGLUND and ARTHUR HADDOCK, citizens of the United States, residing at West Long Branch, in the county of Monmouth and State of New Jersey, and at East Orange, in the county of Essex and State of New Jersey, respectively, have invented a new, original, and ornamental Design for Loop Antennae, of which the following is a specification, reference being had to the accompanying drawings forming a part thereof.

The figure is a view in perspective of a loop antenna illustrating our new design.

We claim:

The ornamental design for a loop antenna as shown.

In witness whereof, I hereunto subscribe my name this 22 day of May A. D., 1923.

CARL R. ENGLUND.

In witness whereof, I hereunto subscribe my name this 22 day of May A. D., 1923.

ARTHUR HADDOCK.
